(57) **CLAIM**

The ornamental design for the electronic computer, as shown and described.

DESCRIPTION

FIG. 1 is a perspective view of an electronic computer showing our new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof;

FIG. 7 is a bottom plan view thereof;

FIG. 8 is a perspective view thereof; and,

FIG. 9 is another perspective view thereof.

Broken lines shown in the drawings illustrate portions of the electronic computer, and form no part of the claimed design.
